UNITED STATES PATENT OFFICE

PETER MATTNER, OF ST. LOUIS, MISSOURI, ASSIGNOR TO JOHNSON-STEVENS & SHINKLE SHOE COMPANY, OF ST. LOUIS, MISSOURI, A CORPORATION OF MISSOURI

PROCESS AND APPARATUS FOR WEAVING FABRICS

Application filed November 13, 1929. Serial No. 406,742.

This invention pertains to weaving and more particularly to a process and mechanism adapted for weaving fabrics from strips of leather or the like.

In the manufacture of certain types of shoes the uppers are constructed of a woven fabric of leather strips. In many styles the fabric is woven of strips of different color so as to obtain decorative effects. The decorative effect is greatly enhanced by weaving into the fabric a suitable pattern carried out in different colors of leather.

One of the objects of this invention, therefore, is to provide an apparatus for weaving fabrics of strips of materials capable of automatically weaving a pattern into the fabric.

Another object is to provide such a machine in which the pattern may be changed in a convenient manner.

Another object is to provide such a machine which will automatically weave a predetermined pattern and in which such a pattern will be repeated at definite intervals.

Another object is to provide mechanism whereby the pattern may be changed by a simple operation of the machine.

Another object is to provide a machine whereby the patterns in three or more different colors may be executed.

Another object is to provide a machine which will receive the raw material in the form of a broad band, cut the bands into strips suitable for weaving and weave the cut strips into a suitable fabric.

Another object is to provide such a machine whereby a plurality of bands of different colored materials may be supplied to the machine and which will cut the same into strips and arrange the cut strips to provide the warp for a suitable fabric.

Another object is to provide a novel process for forming the warp for weaving such fabrics.

Further objects will appear from the following description taken in connection with the accompanying drawings, in which:

Figure 1 is a side view of the machine embodying this invention.

Figure 2 is a detailed view somewhat enlarged taken about on line 2—2 of Figure 3.

Figure 3 is a detailed view somewhat enlarged taken about on line 3—3 of Figure 1.

Figure 4 is an enlarged detailed plan view of the tensioning device shown in Figure 1.

Figure 5 is an enlarged detailed view of 55 the selector drum.

Figure 6 is a transverse section of Figure 5.

Figure 7 is a detailed view of the driving movement for the selector drum.

Figure 8 is a perspective detail of a means 60 for locking the drum.

Figure 9 is an enlarged detailed view illustrating the feeding and cutting of a plurality of bands of material; and

Figure 10 is a plan view of Figure 9 showing 65 the spreading of the strips to form the warp.

Referring now to the drawings, 1 designates a frame which may be of angle iron or other suitable material and upon which the other mechanism is mounted. Mounted on the frame 1 is a superstructure 2 which carries a plurality of heddles 3 which may be similar in construction and arrangement to the heddles of any ordinary loom. The heddles 3 are each connected by a spring 4 to a transverse bar 5 on the frame 1.

At their upper ends, the heddles 3 are each hung upon a chain 6 or other flexible tension member passing over pulleys 7 and secured at its 70 other end to a vertically movable actuator 8.

It will be seen, therefore, that downward movement of any actuator will operate to raise the corresponding heddle. Each actuator 8 is provided at its upper end with a 75

rearwardly extending hook 9 adapted to engage the horizontal cross bar 10 on the superstructure 2. Engagement of the hook 9 with the bar 10 fixes the normal position of the actuator 8 and its corresponding heddle. 80

Each actuator is provided near its lower end with a forwardly projecting lug or cam 11 and at its lower end with a rearwardly directed hook 12.

Mounted for vertical sliding movement 95 in a guide 13 on the frame 1 is a bar 14 carrying at its upper end a transverse bar 15. The lower end of the bar 14 has pivoted thereto a link 16 whose lower end is pivotally connected at 17 with an arm 18 pivoted at its other 100

end to a bracket 19 mounted on the frame 1. The arm 18 carries a cam roller 20 engaging a cam 21 on a countershaft 22 which is geared to another countershaft 23 driven by a motor 24. The form of the cam 21 is such that upon rotation thereof the arm 18 is periodically swung up and down so as to impart to the bars 14 and 15 a periodic up and down movement. The bar 15 is thus adapted to provide a driver for the actuators 8 as will presently be more fully described.

Mounted for rotation in a rocking bracket 25 pivoted at 26 on the superstructure 2 is a drum 27. The drum 27 has a shaft 28 which carries at one end a ratchet wheel 29. The spring-pressed pawl 30 is pivoted to a bell crank 31 rocking on the shaft 28 and whose other arm is pivoted to a link 32. The link 32 extends downwardly and is pivoted at 20 its lower end to a lever 33 pivoted at 34 to the bracket 19 and carrying at its other end a cam roller 35, engaging a cam 36 on the shaft 22. Rotation of the shaft 22 will, therefore, cause the link 32 to reciprocate vertically thereby rocking the bell crank 31 so as to cause the pawl 30 to rotate the ratchet wheel 29 and, therefore, the shaft 28 and the drum 27 intermittently in accordance with the movement of the link 32.

30 The drum 27 is provided with a series of threaded sockets 37 adapted to receive the corresponding threaded ends of a series of selectors 38. The selectors 38 extend outwardly from the drum 27 so that when properly aligned they will engage the lugs 11 on the actuator 8 as the drum rotates. Such engagement will cause the rotation of the drum to move the selector against the cam 11 so as to swing the actuator 8 rearwardly 40 to such a position that its hook 12 will engage the lower edge of the driver 15 when the latter reaches the upper end of its travel. Such engagement will then cause the actuator 8 to be carried downwardly by the next stroke 45 of the driver thereby raising the corresponding heddle 3. Upon the succeeding upward stroke of the driver 15 the hook 9 of the actuator 8 will be brought into engagement with the cross bar 10 which provides a stop 50 tending to arrest the movement of the actuator which thereupon pivots about the stop 10 so as to carry the hook 12 out of engagement with the driver 15.

It will be seen that this mechanism provides that upon rotation of the shaft 22 the driver 15 will be moved up and down periodically and the drum 27 will be rotated intermittently. The relation is such that at each reciprocation of the driver 15 the drum is rotated so as to bring a succeeding row of selectors 38 into engagement with the actuators. Accordingly, at each stroke of the driver a different set of selected actuators may be placed in engagement therewith 60 so that an appropriate group of heddles will

be lifted to form the shed for weaving the fabric. After each shed is formed, the operator passes a strip of material there-through transversely in the usual manner and drives the same home by means of a bat- 70 ten 39. As the selectors 38 may be positioned on the drum 27 in any predetermined arrangement, the heddles 3 may be lifted in such sequence as to form a desired pattern in the fabric.

75 The selectors 38 may be arranged on the drum 27 in two or more groups. In the embodiment illustrated in the drawings, two groups are used. As shown in Figure 2 the selectors opposite the two right hand actuators are arranged in alignment with those actuators and in such a manner as to move those two actuators automatically into engagement with the driver 15. It will be noted that the remaining selectors are positioned out of alignment with the remaining actuators so as to be inoperative for moving the latter. This, therefore, forms two groups of selectors only the first of which is operative. As the heddles corresponding to this group 80 are arranged to lift alternate strips of the warp, the adjustment of the machine will weave a basket pattern.

85 The other group of selectors which in the case illustrated includes all the other selectors in the drum may be arranged to weave a more complicated pattern. In order to bring this group into operative relation with the actuators, the drum 27 is moved axially to bring these selectors into alignment with their respective actuators. In order to accomplish this, the bracket 25 is fixed to its pivot bar 26 which is slidable in bearings 40 on the superstructure 2. The bar 26 carries a locking ring 41, (see Fig. 8), adapted to 90 engage either one of two notches 42 in a bar 43 on the superstructure 2 to lock the rod 26 against endwise movement. This fixes the position of the bracket 25 with a given group of selectors in alignment with their actuators. The ring 41 has a notch 44 which, when the bracket 25 is rocked forwardly 95 against the tension of a spring 45, registers with the bar 43 so as to permit endwise movement of the bracket. The bracket may be 100 shifted endwise, a distance equal to half the interval between the selectors so as to bring the other group of selectors into alignment with their actuators. This also moves the ring 41 into registry with the other notch 42 so that when the bracket is released and moved back to its normal position by the spring 45 the ring 41 will enter 105 the other notch 42 and again lock the drum 110 in its new position.

115 Accordingly, the selectors may be arranged in a plurality of different groups each adapted to weave a different pattern and the drum may be shifted selectively to one or another 120

group without any other adjustment of the machine.

The material which is to form the warp is sent to the machine in the form of a broad band 46. The band 46 passes through a tensioning device comprising a series of rollers 47 mounted in a bracket 48 and arranged so that the band may be passed around said rollers successively as shown in Figure 1. A pair of guides 49 may be slidably mounted upon the rollers 47 and arranged to be adjusted toward or from each other by means of a screw 50 having right and left hand threads engaging their respective guides as indicated in Figure 4. These guides may thus be adjusted to the width of the band 46.

Pivoted at 51 in the bracket 48 is a pair of arms 52 carrying at their upper ends a roller 53. The arms 52 are each provided with an extension 54 engaged by a spring 55 to tension the arms 52. A strip 56 loosely mounted in the bracket 48 is yieldingly forced into engagement with a corresponding stationary strip 57 fixed to the bracket 48. The tension on the strip 56 is provided by a screw 58 adjustably mounted in an arm 59 fixed to the pivot rod 51. The springs 55 acting through the rod 51 tension the arm 59 so as to force the screw 58 against the strip 56.

The band 46 is passed downwardly between the strips 56 and 57 which provides a brake for tensioning the band. The latter then passes around the roll 47 as shown in Fig. 1, and usually under the roller 53 which is also tensioned by the arms 52. The band then passes over guiding rollers 60 similar to the roller 47 and thence between a series of cutting wheels 61 and a platen or backing roll 62. The cutter 61 and the roll 62 are driven by a suitable gear from a shaft 63 which in turn is driven by a chain 64 from the shaft 23 as indicated in Figure 1. For a detailed description of these cutters reference may be had to applicant's pending application Serial No. 349,337, filed March 23, 1929.

The cutters 61 cut the band 46 into narrow strips as indicated in Figure 10. Either a single band of material may be used or several bands may be passed through the cutters simultaneously as indicated in Figure 9. As the bands may pass through the cutters in superimposed relation, the cut strips must be spread apart as indicated in Figure 10. A suitable spacer frame 65 may be mounted on the frame 1 to maintain the strips in suitable spaced relation.

The operation of this apparatus is, therefore as follows: The band 46 which may be either one or a plurality of different bands is passed through the tensioning device to the cutter. The cut strips are then passed through the spacer frame 65, if necessary, and then through the heddles 3. The grouping of the strips in the heddles 3 will, of

course, be arranged in accordance with the pattern to be woven.

The selectors 38 are arranged on the drum in such a way as to provide the weaving of the desired pattern. When the motor 25 is started the driver 15 is driven with a vertical up and down movement. At the same time the drum 27 is rotated one step at a time by the action of the link 32. The movement of the drum is timed with that of the driver so that at each stroke of the driver a new set of selectors will be moved to operate the corresponding actuators 8. The actuators engaged by the selectors 38 are moved rearwardly so that the hooks 12 thereof engage the driver 15 which then descends carrying the selected actuator downwardly and raising the corresponding heddles 3. Upon the return stroke of the driver 15 the hooks 9 of the rising actuators engage the stop 10 so that their lower ends are carried forwardly to disengage them from the driver. In this way the heddles 3 are raised in a predetermined sequence in accordance with the arrangement of the selectors 38 on the drum.

The selectors may be arranged in two or more different groups on the drum and the drum is arranged to be shifted so as to bring any desired group of selectors into alignment with their respective actuators. Accordingly, the adjustment can be shifted instantly to change the pattern woven.

By passing the material through the machine in a plurality of bands of different colors, a warp is provided having a variety of different colored strands so that a great variety of color patterns may be produced by the automatic operation of a machine.

The guide roller and tension devices insure that the band 46 will be fed to the cutters in a smooth and even manner so that the cut strips will all be of uniform and equal width.

It will be seen, therefore, that this invention provides a process and apparatus whereby a plurality of broad bands of material may be cut into narrow strips and a fabric woven from the cut strips in a single operation. Various designs may be worked into the resulting fabric by providing the original bands in different colors and arrangements. The apparatus insures that strips of uniform width are produced and arranged to form the warp for the woven fabric and any desired sequence or arrangement of strips may be maintained. Accordingly fabric of a great variety of designs may be produced in a simple and expeditious manner.

While this apparatus has been described as a unitary machine, it will be understood that certain individual features and sub-combinations may be useful alone or without reference to other features thereof. It is under-

stood accordingly, that the employment of such individual features and sub-combinations is contemplated by this invention and is within the scope of the appended claims.

5 It is further obvious that various changes may be made, within the scope of the appended claims, in the details of construction without departing from the spirit of this invention. It is, therefore, to be understood 10 that this invention is not to be limited to the specific details shown and/or described.

Having thus described the invention, what is claimed is:

15 1. In the art of weaving fabrics, the process comprising, feeding a plurality of broad bands of material in layers, cutting thru the layers to cut the bands into strips, and spreading the cut strips to provide the warp for the woven fabric.

20 2. In the art of weaving fabrics, the process comprising, feeding a plurality of broad bands of material in layers, cutting thru the layers to cut the bands into strips, and spreading the cut strips from different bands 25 in a definite relative order to provide the warp for the woven fabric.

30 3. In the art of weaving fabrics, the process comprising, feeding a plurality of broad bands of different colored materials in layers, cutting thru the layers to cut the bands into strips, and spreading the cut strips to provide the warp for the woven fabric.

35 4. In the art of weaving fabrics, the process comprising, feeding a plurality of broad bands of different colored materials in layers, cutting thru the layers to cut the bands into strips, spreading the cut strips to provide the warp for the woven fabric, and manipulating the cut strips of different colors so as to 40 weave a pattern.

45 5. A machine for weaving fabrics, comprising, weaving mechanism adapted to receive a warp composed of flat strips, means for feeding a broad band of material, means for cutting the band into a plurality of flat strips to provide the warp for said weaving mechanism, and means for tensioning and flattening the band as it approaches said cutting means.

50 6. A machine for weaving fabrics, comprising, weaving mechanism adapted to receive a warp composed of flat strips, means for feeding a broad band of material, means for cutting the band into a plurality of flat strips to provide the warp for said weaving mechanism, and means for guiding the band to said cutting means including band retarding means and yielding band tensioning means between said retarding means and said cutting means.

65 7. A machine for weaving fabrics, comprising, weaving mechanism adapted to receive a warp composed of flat strips, means for feeding a broad band of material, means for cutting the band into a plurality of flat

strips to provide the warp for said weaving mechanism, and means for guiding the band to said cutting means including an adjustable brake having jaws adapted to clamp the band with yielding pressure.

70 8. A machine for weaving fabrics, comprising, weaving mechanism adapted to receive a warp composed of flat strips, means for feeding a broad band of material, means for cutting the band into a plurality of flat 75 strips to provide the warp for said weaving mechanism, and means for guiding the band to said cutting means including an adjustable brake having jaws adapted to clamp the band with yielding pressure, and yielding 80 band tensioning means between said brake and said cutting means.

In testimony whereof I affix my signature this 24th day of October, 1929.
